UNITED STATES PATENT OFFICE.

ADOLPH K. MALMQUIST, OF SOUTH BELLINGHAM, WASHINGTON, ASSIGNOR TO MALMQUIST MACHINE COMPANY, OF SOUTH BELLINGHAM, WASHINGTON.

CAN-CAPPING MECHANISM.

Application filed October 20, 1921. Serial No. 508,920.

To all whom it may concern:

Be it known that I, ADOLPH K. MALMQUIST, a citizen of the United States, and a resident of South Bellingham, in the county 5 of Whatcom and State of Washington, have invented certain new and useful Improvements in Can-Capping Mechanism; and I do hereby declare the following to be a full, clear, and exact description of the invention, 10 such as will enable others skilled in the art to which it appertains to make and use the same.

This invention relates to improvements in can capping mechanism and more particularly to such as are adapted for use with 15 canning machines for double seaming caps to cans, one object of the invention being to provide a seaming mechanism operable with modern high speed machines, which 20 shall be simple and compact in construction and in which adequate means shall be provided to effect adjustments of various parts to insure accurate and efficient operation of the mechanism.

With this and other objects in view, the 25 invention consists in certain novel features of construction and combinations of parts as hereinafter set forth and pointed out in the claims.

In the accompanying drawings Figures 1, 30 2 and 3 are vertical transverse sectional views showing parts of the mechanism in different positions; Figure 4 is a horizontal sectional view on the line 4—4 of Figure 1; Figure 5 is a bottom plan view; Figures 6 and 7 are detail views showing the spider in which the levers carrying the seaming 35 rollers are mounted; Figure 8 is a view in elevation of the cam head for operating the seaming roller levers; Figure 8^a is a bottom plan view of said head; Figures 9 and 10 are views of the lever for operating said cam 40 head, and Figure 11 is a view of the ring 46.

The mechanism for accomplishing the 45 seaming operations of caps to can bodies, is supported by framework 1 forming an enclosing casing,—two sides 2, 2 and top members 3, 4 of which may be removably secured in place by suitable fastening devices 5 and 50 leakage past these removable parts of the framework or casing is prevented by means of interposed gasketing material 6.

In Figure 1 of the drawings, I have shown 55 the framework or casing as being mounted upon the top member 7 of a can filling and

sealing machine, the latter having a chamber 8 in which the filling and sealing may be accomplished, and said machine is provided with a platform 9 for raising and lowering the can to be sealed. Figure 1 also shows 60 a movable can platform 10 for raising a can to filling means indicated at 11, and it is the intention that during the filling and sealing of the cans in the chamber 8, said chamber shall be in a vacuous condition. 65 The construction and arrangement of the means for exhausting the chamber 8, for operating the can platforms and for operating the filling means, do not constitute parts of my present invention and need not be 70 shown and described herein.

When my improvements are employed with a canning machine comprising a plurality of can filling and sealing chambers 75 movable relatively to the seaming mechanism, the casing or framework of the latter will be provided at its bottom with a gasket or gaskets such as indicated at 12 to engage the top of the filling and sealing chambers, it being understood that openings 80 such as shown at 13 are provided in the tops of said chambers to permit access of the cans and caps to the seaming mechanism located within the enclosure formed by the frame or casing 1.

The framework or housing 1 for the seaming mechanism includes in its upper portion, a fixed tubular head or member 14 which is internally threaded to receive the externally threaded upper portion of a tubular 90 upright 15, the latter constituting the fixed shaft or stem of a chuck 16 formed integral with its lower end. The chuck and its stem are held in proper position by means of nuts 17, 17^a screwed on the upper threaded 95 portion of the latter above and below the fixed head 14 and adapted to bear against the latter. By loosening these nuts, the chuck stem may be turned to effect vertical 100 adjustment of the chuck.

A bushing 18 is revolvably mounted on the tubular upright or stem 15 of the chuck 16 and between the lower end of said bushing and the chuck, anti-friction bearing devices 19 are located. Fitted tightly on the bushing 18 so as to be rotatable therewith, is a spider or carrier 20 (Figures 6 and 7) having an annular series of recesses 21 and grooves 21^a constituting upward extensions of said recesses, six such recesses and 110

grooves being shown in the drawings. The spider is also formed approximately midway between its ends with shoulders 22 and at its lower end with a series of depending 5 fingers 23, the latter terminating at their lower ends in close proximity to the chuck 16, for purposes hereinafter explained.

Pivotedly supported in the recesses 21 of the spider are two sets of levers 24, 24^a, 10 the levers 24 alternating with the levers 24^a, and the pivotal supports of the former being in a higher plane than that of the pivotal supports of the latter. Six levers 24—24^a (three of each) are employed and their lower 15 arms 25 are approximately horizontal to receive the mountings of seaming rollers 26, 26^a respectively, the construction of each of said levers arms and roller mountings being as follows: The horizontal arm 25 of 20 each of said levers is bifurcated and formed with an opening 27 (Fig. 5) for the accommodation of an externally threaded sleeve 28, which latter may be clamped in said arm by means of a bolt 29. The sleeve 28 is also 25 threaded internally to receive an externally threaded spindle 30 on which a seaming roller (26 or 26^a) is mounted through the medium of interposed roller bearings 31. The spindle 30 is provided at its lower end 30 with a head 32, so as to be disposed under the seaming roller and the lower end of the sleeve 28 is provided with a head 33 disposed over said roller. A nut 34 is screwed on the upper portion of the sleeve and bears upon 35 the upper face of the lever arm 25, and a nut 35 screwed on the upper portion of the spindle 30 bears on the upper end of the sleeve 28. By loosening the nut 34, the sleeve 28 may be turned to effect vertical adjustment of the seaming roller relatively to 40 the chuck 16.

Upon the upper ends of the seaming roller levers (24—24^a) contact plates 36 are mounted for cooperation with a cam head 45 37 and upon each of the contact plates 36, a plate 38 is mounted and provided at its outer end with a curved upward projection 39. A bolt 39^a passes through a hole in each 50 plate 38 and through an elongated hole in the underlying contact plate, the thread portion of said screw entering the lever 24 or 24^a. A horizontally disposed screw 40 enters a suitable hole or socket in said lever and the circular head 40^a of this screw enters a 55 groove or slot 41 in the contact plate 36. By loosening the screws 39^a and turning the screws 40, (when the contact plates 36 are bearing against the cam head 37) the levers 24, 24^a may be so moved as to effect horizontal adjustment of the seaming rollers 60 relatively to the chuck.

A circular coiled spring 42 is seated in the curved projections 39 of the several plates 38 and serves to press the contact plates 36 65 of the levers 24, 24^a toward the cam head

37 and the seaming rollers 26, 26^a away from the chuck 16.

The cam head 37 comprises a plurality of sets of cam arms 37^a, 37^b, the arms of one set alternating with those of the other set, 70 and in the present instance said cam head is made with three cam arms 37^a and three cam arms 37^b. The cam head 37 is movable longitudinally on the bushing 18 and is made with an exteriorly threaded sleeve or hub 37^c 75 surrounding the latter. The arms of the cam head 37 are movable longitudinally in the grooves 21^a of the spider 20 and serve to cause said cam head and spider to rotate together. Each cam arm 37^a is made with cam faces *a*, *b*, *c* with which co-operate the contact plates 36 of the levers 24 and the cam arms 37^b are made with cam faces *d*, *e*, *f*, with which co-operate the contact plates 36 of the levers 24^a whereby said levers will be 80 operated for manipulating the seaming rollers when the cam head 37 is moved longitudinally.

A bearing ring 43 is located on the cam head around the hub portion 37^c thereof and above said bearing ring, another bearing ring 44 is screwed on said hub portion and held in adjusted position by a ring 45 threaded on said hub portion. Between the bearing rings 43 and 44, a ring or annular 90 carrier 46 is located and receives balls 47 which have bearings against the two bearing rings 43—44. The ring or ball carrier 46 is provided with diametrically opposite upwardly projecting arms 48, the upper ends of which are pivotally connected with the forked arms 49, 49 of a lever 50 (Figures 9 and 10). At its other end, this lever is provided with a laterally projecting hub portion 51 which is mounted on a cam shaft 100 52 suitably journaled in the framework. At one end the cam shaft is provided with a flange 53, resting against the framework and secured thereto by a bolt 54 passing through a slot in said flange. At the other 110 end of the cam shaft 52, a bolt 55 enters the same, and between the head of this bolt and the framework, a washer 56 is disposed. By tightening the bolts 54 and 55, the cam shaft 52 will be held normally in fixed position. For lubricating the bearing of the hub of lever 50 on the cam shaft, the latter may be provided with a duct 56 to receive lubricant from a cup 57. Intermediate of its ends, the lever 50 is made with an elongated 120 opening 58, near respective ends of which, arms 59, 59 are provided on said lever. A shaft 60 passes through the opening 58 in the lever 50 and suitable bearing boxes 61 are provided for this shaft. A lubricant duct 62 may be located centrally within the shaft 60 to receive lubricant from a cup 63 and distribute the lubricant by lateral ducts to the bearings of said shaft. If desired, a bolt 64 may be passed through the end of one 130

of the bearing boxes and engage one end of the shaft 60 to hold the latter against longitudinal movement.

A cam 65 is secured to the shaft 60 in position to be disposed between the arms 59, 59 of the lever 50 so that when said shaft is turned, the lever 50 will be raised or lowered on its bearing on the cam shaft 52 as a fulcrum, and thus effect vertical sliding movement of the cam head 37 to operate the seaming roller levers 24, 24^a. It will be observed that by loosening the bolts 54 and 55 (which normally hold the cam fulcrum-shaft 52 of lever 50 in fixed position) and then turning the cam shaft 52, the lever 50 may be so moved as to effect vertical adjustment of the cam head 37.

A main driving shaft for the mechanism is shown at 66 and is mounted in suitably lubricated bearings in the framework. A horizontally disposed gear wheel 67 is mounted, through the medium of ball-bearing devices 68, on the shaft 66 and transmits motion to a gear wheel 69 secured to the shouldered portions of the spider for rotating the latter and the parts connected therewith, said gear wheel 69 being provided with recesses 70 for the accommodation of the seaming roller levers 24, 24^a.

The main driving shaft 66 has secured thereto, a worm 71 which transmits motion to a worm wheel 72 secured to the shaft 60, whereby said shaft will be rotated and cause cooperation of the cam with the arms 59 on lever 50 to operate the latter and the cam head as previously explained.

The spindle 73 of a cap and can guide head 74 passes freely through the tubular shaft 15 of the chuck. The bore in the lower portion of the tubular shaft 15 is enlarged for the accommodation of a spring 75 which encircles the spindle 73 and bears at its respective ends against a shoulder 76 and the guide head 74, the construction being such that the spring will normally position the guide head below the chuck 15 and below the plane of the rollers, as shown in Figure 1. The upper projecting end of the spindle 73 is threaded and has secured thereto, a release bracket 77 which is held in place by a nut 78 screwed in said spindle. The bracket 77 projects downwardly and is provided with an arm 79 disposed near the shaft 60 and is provided with a lug 80 to be engaged by a lug or cam 81 on a wheel or disk 82 secured to the shaft 60.

The spring-pressed head 74 serves not only to guide the cap and can to the seaming chuck, but it also serves to force the sealed can away from the seaming mechanism. The speed of the shaft 60 will be such that after the seaming operation shall have been completed and the can is ready to descend, the cam lug 81 on the wheel or disk 82 will engage the lug 80 on the arm 79 of bracket

77 and force the latter downwardly, thus forcibly lowering the spindle 73 and guide head 74 and forcing the sealed can downwardly in the event that the spring 75 would fail (by reason of sticking of the sealed can in the seaming mechanism) to promptly force the head 74 downwardly to release the can.

In the operation of the mechanism, with the parts in the positions shown in Figure 1 and the seaming devices ready to receive a cap and can, the can will be raised and receive a cap and as it continues to rise (with the cap thereon) the cap will engage the guide head 74 and move the same upwardly until the upper end of the can and the cap shall be presented to the chuck 16. The cam head 37 will be moved downwardly and the cooperation of its cam arms with the contact plates 36 on the levers 24, 24^a will turn said levers on their fulcrums and move the sets of rollers 26, 26^a toward the chuck so as to cause the sets of rollers to perform, successively the two and double seaming steps to seal the cap to the can. The rollers 26 will operate to perform the first bending of the metal of the cap and can in forming the seam and the rollers 26^a will operate to complete the seaming to insure the air tight closure of the can, and the cap will be very quickly seamed to the can during the revolution of the spider which carries the seaming roller levers and seaming rollers. In the drawings, I have shown three rollers for the first seaming operation and three for the finishing operation, but if desired, I might employ four rollers for one seaming operation and two rollers for the other operation. The employment of six seaming rollers is of great advantage for high speed machines where the time for closing a can is very short. By the employment of six seaming rollers, the seam will be even and the structure embodying the levers which carry the rollers mounted in the spider will be properly balanced and vibration and wear will be reduced to a minimum.

If for any reason, no cap would be in position when a can is raised to the seaming mechanism, the upward movement of the open can will be limited by engagement with the fingers 23 depending from the spider 20 and the can flange will thus be prevented from being rolled over back of the chuck 16. When the upper edge of the open can is limited in upward movement by the fingers 23, the seaming rollers will roll the can flange down and allow can to descend when its supporting platform descends. While the unsealed can would be spoiled, the machine would not have to be stopped to remove it.

In Figure 1 of the drawings, the cam head 37 is shown at its extreme up-stroke and in Figure 2 it is shown in its extreme

down-stroke, while in Figure 3, the position which the cam head takes during the finishing of the seaming operation is shown. When the seaming of a cap to a can is finished and the capped can descends the cam head 37 will assume the position shown in Figure 2 and while the finished can is being discharged and the next can is coming to position to be raised to the seaming mechanism and when the second can is in such position, the cam head 37 will have moved up to the position shown in Figure 1 and the seaming rollers will be wide open and the can and cap will be moved to the chuck. 15 The downward movement of the cam head from the position shown in Figure 1 will now cause operation of the levers 24, 24^a to move the seaming rollers 26, 26^a and effect the seaming of the cap to the can. 20 Since my improvements are intended to be embodied in a machine for sealing the cans in vacuum, it is desirable that the free space within the casing shall be reduced to a minimum so that said casing may contain a minimum amount of air to be exhausted, and to accomplish this, blocks 83 are secured within the closure.

Various changes might be made in the details of construction of my invention without departing from the spirit thereof or limiting its scope and hence I do not wish to restrict myself to the precise details herein set forth.

Having fully described my invention what I claim as new and desire to secure by Letters Patent, is:—

1. In can capping mechanism, the combination with framework, of a chuck, a revoluble carrier, levers pivoted to said carrier, each of said levers provided with a lower horizontal arm having an opening, a sleeve threaded through said opening in each lower lever arm, a spindle threaded through each sleeve, a seaming roller mounted on each spindle, a nut on the upper portion of each sleeve, a nut on the upper portion of each spindle, and means for operating said levers.

2. In can capping mechanism, the combination with framework, and a chuck, of a carrier revolubly mounted relatively to said chuck, levers pivotally supported by said carrier, seaming rollers carried by the lower arms of said levers, a vertically movable cam head revoluble with said carrier, contact plates carried by the upper arms of said levers and cooperable with the cam head, each plate having a recess, means normally clamping said plates in position, and a screw entering each lever and having a head entering the recess of the adjacent contact plate, whereby said contact plates may be adjusted to effect horizontal adjustment of the seaming rollers relatively to the chuck.

3. In can capping mechanism, the combination with a rotatable carrier, of two sets of pivoted levers mounted in said carrier, the levers of the two sets aggregating six, the pivotal mountings of the levers of one set being located on a higher plane than that of the pivotal mountings of the levers of the other set, a seaming roller carried by each lever of each set, and means for operating said levers. 75

4. In a can capping machine, the combination with a rotatable carrier, of two sets of three levers each pivotally supported by said carrier, the levers of one set having pivotal mountings on a higher plane than the pivotal mountings of the levers of the other set and the levers of one set alternating with the levers of the other set, a seaming roller carried by each lever, and means for operating said levers. 80

5. In can capping mechanism, the combination with framework, and a chuck, of six seaming rollers, one set of said rollers being adapted to effect one step of a seaming operation and the other set of said rollers adapted to effect the finishing step of said seaming operation, a longitudinally movable cam head having two sets of cam faces for effecting operation of the two sets of seaming rollers in succession, means for revolving said rollers about the chuck, and means for operating the cam head. 90

6. In can capping mechanism, the combination with framework, a vertical tubular shaft secured to the framework, a chuck at the lower end of said shaft, seaming rollers about said chuck, means for supporting said seaming rollers, means for operating said seaming rollers, a spindle longitudinally movable through said tubular shaft, a head at the lower end of said spindle, a spring acting normally to force said spindle and head downwardly, and means operable automatically to force said spindle and head downwardly upon failure of said spring. 100

7. In a can capping mechanism, the combination with framework, a tubular upright shaft provided at its lower end with a chuck, seaming rollers, operating means, and a driving shaft for said operating means, of a spindle longitudinally movable through said tubular shaft and provided with a head at its lower end, a bracket secured to said spindle, a shaft mounted in the framework, a cam carried by said shaft and cooperable with said bracket to force the spindle and head downwardly, and gearing between said shaft and the driving shaft. 115

8. In can capping mechanism, the combination with framework, a driving shaft, and seaming mechanism, including a chuck, a revoluble carrier, levers pivotally supported by said carrier, seaming rollers carried by said levers, and a longitudinally movable cam head rotatable with said carrier, of an 120

- operating lever, connecting means between one end of said operating lever and said cam head, a pivotal mounting for one end of said lever, said lever having an elongated opening between its ends, a shaft mounted in the framework, a cam carried by said shaft and cooperable with said lever, and gearing between said shaft and the driving shaft.
- 10 9. In can capping mechanism, the combination with framework, a driving shaft, and seaming mechanism, including a chuck, a revoluble carrier, levers pivotally supported by said carrier, seaming rollers carried by said levers, and a longitudinally movable cam head rotatable with said carrier, of an operating lever, connecting means between one end of said operating lever and said cam head, a pivotal mounting for one end of said lever, said lever having an elongated opening between its ends, a shaft mounted in the framework, a cam carried by said shaft and cooperable with said lever, means for adjusting said pivotal mounting to effect vertical adjustment of the cam head, and gearing between said shaft and the driving shaft.
- 15 10. In can capping mechanism, the combination with framework, and a chuck, of a carrier, can limiting devices depending from said carrier and terminating near the chuck, levers pivotally supported by said carrier, seaming rollers carried by said levers, and means for operating said levers.
- 20 11. In can capping mechanism, the combination with framework, an upright shaft, and a chuck at the lower end of said shaft, of a carrier revoluble about said shaft, said carrier having recesses and grooves communicating with said recesses, levers pivoted between their ends in said recesses, seaming rollers carried by the lower arms of said levers, a cam head longitudinally movable relatively to said carrier and having cam arms movable in the grooves of said carrier and cooperable with the upper arms of said levers, means for moving said cam head, and means for rotating the carrier and parts rotatable therewith.
- 25 12. In can capping mechanism, the combination with framework, an upright shaft, and a chuck at the lower end of said shaft, of a carrier revoluble about said shaft, said carrier having recesses and grooves communicating with said recesses, levers pivoted between their ends in said recesses, seaming rollers carried by the lower arms of said levers, a cam head longitudinally movable relatively to said carrier and having cam arms movable in the grooves of said carrier and cooperable with the upper arms of said levers, means for moving said cam head, a driving shaft, a gear thereon, a gear secured to said carrier and meshing with the gear on the driving shaft, and means operable by the driving shaft for operating the cam head moving means.
- 30 13. In can capping mechanism, the combination with framework, a chuck, a revoluble carrier, levers pivotally supported by the carrier, and seaming rollers carried by said levers, of a longitudinally movable cam head for operating said levers, of an operating lever, a ball ring connected with said cam head, bearings for balls carried by said ring, arms on said ball ring, an operating lever having forked arms at one end connected with the arms of the ball ring, a pivotal mounting for said operating lever, and means for operating said operating lever.
- 35 40 In testimony whereof, I have signed this specification.

ADOLPH K. MALMQUIST.
